By Lynn H. Latta - Atty.

UNITED STATES PATENT OFFICE.

JOHN B. WANKO, OF SIOUX CITY, IOWA.

WAVE-BATH MACHINE.

Application filed May 1, 1926. Serial No. 106,173.

My invention relates to a device for bathing the human body.

The object of my invention in general is to provide a device in which a person may 5 bathe without exerting any energy, and in which the water is so agitated around the body of the bather that a very soothing sensation will be experienced which will tend toward relaxation of the muscular and nervous 10 system, while serving to wash foreign matter from the pores.

Another object is to provide in such a device a tub in which the person desiring to bathe may recline, together with means for 15 producing longitudinal rocking wave motion of the water within the tub in such a manner that the water will flow around the body of the person in a direction longitudinal of the tub, and also will rise and fall 20 vertically around the body of the person.

More particularly my invention is embodied in a device employing an elongated tub, the ends of which are preferably curved in such a manner as to augment the above- 25 described wave motion, and which is provided with an oscillated paddle, the lower end of which is immersed in the water of the tub, and separated from the body of the tub, by a partition which does not interfere 30 with the wave motion produced, but allows the two bodies of water, which it separates, to move as a single unit.

With these and other objects in view, my invention consists in the construction, arrangement and combination of the various 35 parts of my device, whereby the objects contemplated are attained, as hereinafter more fully set forth, pointed out in my claims and illustrated in the accompanying drawings, in which:

Fig. 1 is a side elevation of my invention.

Fig. 2 is a vertical, longitudinal, sectional view through the tub, a person reclining therein being illustrated in dotted lines.

Fig. 3 is a plan view of the invention, the motor casing being shown in section, and

Fig. 4 is a vertical, transverse, sectional view through the tub.

I have used the reference character 10, in 50 Fig. 3, to indicate generally the wall of a room in which my invention is installed.

A casing, 11, is built into the wall, 10, and serves to house the motor apparatus, which I have indicated generally by the reference character, A.

The apparatus, A, includes a small electric motor, 12, the shaft of which carries a pinion, 13. A shaft, 14, is journaled in a bracket, 15, supported in the casing, 11, and carries a gear, 16, and a pinion, 17. The gear, 16, meshes with the pinion, 13, and the pinion, 17, in turn meshes with a gear, 18, supported on a shaft, 19, which is journaled also in the bracket, 15.

The motor, 12, imparts rotation to the 65 gear, 16, by means of the pinion, 13, and the gear, 16, then imparts rotation to the shaft, 14, and to the pinion, 17, which drives the gear, 18.

A crank arm, 20, is secured to the gear, 18, 70 and has a crank throw, 21, on which is journaled the end of the arm, 22, of a pitman, B. The other end of the arm, 22, is slotted, as at 23, to receive bolts, 24, which secure it to the second arm, 25, of the pitman. The 75 bolts, 24, and slot, 23, allow elongation or shortening of the pitman.

The tub is indicated generally at C, and comprise the front side wall, 26, the rear side wall, 27, and the bottom, 28, which is curved 80 upwardly and outwardly as at 29, and thence inwardly, as at 30, substantially as shown in Fig. 1, to form the end walls of the tub.

It will be understood that although a sheet metal tub is shown, the tub might be constructed of wood, tile or cement and serve its function equally well.

Spaced from the wall, 27, is a sheet metal partition, 31, which is supported by brackets, 32 and 33, connecting the partition to the 90 side wall, 27, and to the bottom of the tub, respectively.

A space is left between the edges of the partition and the bottom and end walls of the tub, as indicated at 34. The purpose of 95 so spacing the partition will be more fully explained hereinafter.

A pivot stud, 35, is secured between the partition, 31, and the wall, 27, near the upper edge of the partition, and located substantially midway of the ends thereof.

A paddle, 36, is pivoted intermediate its

ends upon the stud, 35, and depends into the space between the partition, 31, and the wall, 27, to a point near the bottom of the tub. To the upper end of the paddle is secured a 5 yoke member, 37, which is bifurcated to receive the end of the pitman arm, 25, and which secures in place a pin, 38, which connects the pitman with the paddle.

It will now be seen that rotation of the 10 motor will impart reciprocating movement to the pitman and thereby impart oscillating movement to the paddle. The lower end of the paddle will swing back and forth with a pendulum action and the water which has 15 been indicated at 39 in Fig. 2 will be caused to rock back and forth longitudinally of the tub in unison with the paddle.

The partition, 31, does not interfere in the 20 least with the uniform movement of the water. I have found that by imparting rocking motion to the small portion of the body of the water which rests between the partition and the wall, 27, a rocking motion will be 25 imparted to the remainder of the water body as effectively as though the paddle were located centrally between the sides of the tub.

The body of water might be further separated by the partition at the bottom or the 30 ends of the tub, and the same result still obtained, provided that sufficient connection was maintained at either the ends or the bottom between the two sections of that body.

In producing my invention I had in mind 35 eliminating as much as possible any splashing of the water, and I find that by curving the walls as shown the impact of the waves against the end walls of the tub will be less direct, and consequently there will be less tendency for the water to break up at the 40 crests of the swells which are produced alternately at the ends of the tub.

It will be understood that waves are not 45 produced such as the ordinary waves found on bodies of water exposed to the action of the wind, but that the entire body of water will swing from end to end of the tub, producing alternate conditions wherein the water at one end of the tub is much higher than that at the other end, and vice versa. The motion can be most aptly described by 50 the use of the word "rocking".

I find further that the curved ends of the tub tend to augment this rocking motion, 55 whereas a tub provided with straight ends would tend to break it up. This I attribute to the fact that the entire body of water moves back and forth, and in climbing above its normal level at one end of the tub, the inclined plane offered by the curved ends facilitates the raising of the water at that 60 end.

I have shown in Fig. 1, in dotted lines, at 40, the body of a person reclining in the tub. It will be seen that as the water rocks back 65 and forth it will move past the body of the

person in a direction longitudinally of the tub, and will also move vertically as the alternate conditions of depression and swell are produced in the water at the end of the tub wherein the shoulders and head of the 70 person project from the water. If desired, the person may employ the end of the tub as a back rest, and in this position will obtain the greatest benefit from the wave motion produced, since the vertical motion is 75 greatest at the ends of the tub and practically nothing at the center of the tub.

In order to control the speed of the motor, 12, I employ a rheostat, 41, which is connected to the motor by means of wiring, 42, 80 and to a switch, 43, by means of wiring, 44. The switch, 43, may be connected to a transformer or to an ordinary lighting circuit, 45.

Adjustment of the pitman, B, longitudinally will serve to vary the conditions of 85 agitation of the water. For instance, by lengthening the pitman the stroke of the paddle toward the right end of the tub as shown in the drawings will be increased, and the stroke in the other direction decreased. This will serve to increase somewhat the height to which the swell of water reaches at the right end of the tub.

The device as tested out has proved very 90 beneficial to patients wishing to obtain a bath under conditions of relaxation. As before stated, the action of the water tends toward relaxation of the muscular and nervous system and gives a soothing sensation while washing foreign matter from the pores 100 of the bather.

Some changes may be made in the construction and arrangement of the parts of 105 my invention without departing from the real spirit and purpose of my invention, and it is my intention to cover by my claims any modified forms of structure or use of mechanical equivalents, which may be reasonably included within their scope.

I claim as my invention:

1. In a washing machine, a tub having side walls, a bottom and end walls, a partition spaced from one of the side walls to form a large and small compartment, and having its edges spaced uniformly a slight distance from the bottom and side walls so as to substantially form a complete side wall for the large compartment, and a paddle pivoted in the small compartment, said paddle having a depending portion adapted to swing longitudinally of the tub and to transmit to water in the large compartment longitudinally rocking motion.

2. In a washing machine, a tub having side walls, a bottom and end walls, a partition spaced from one of the side walls to form a large and small compartment, and having its edges spaced uniformly a slight distance from the bottom and side walls so as to substantially form a complete side wall

for the large compartment, a paddle pivoted in the small compartment, said paddle having a depending portion adapted to swing longitudinally of the tub and to transmit to water in the large compartment longitudinally rocking motion, a source of power having a rotating crank shaft and a pitman connecting said crank shaft with the paddle for

transmitting movement to said paddle, said pitman being extensible to vary the relative 10 lengths of swing of the paddle on either side of a perpendicular position.

Signed at Sioux City, in the county of Woodbury and State of Iowa, this 14th day of January, 1926.

JOHN B. WANKO.
